J. A. WOODS

COLLAR BURSTER AND EXPANDER

Filed Sept. 2, 1922

UNITED STATES PATENT OFFICE.

JAMES A. WOODS, OF WICHITA, KANSAS.

COLLAR BURSTER AND EXPANDER.

Application filed September 2, 1922. Serial No. 585,976.

To all whom it may concern:

Be it known that I, JAMES A. Woods, a citizen of the United States, and a resident of Wichita, in the county of Sedgwick and 5 State of Kansas, have invented certain new and useful Improvements in Collar Bursters and Expanders, of which the following is a specification.

This invention relates to well drilling 10 equipment and more particularly to a collar burster.

Briefly stated an important object of this invention is to provide a collar burster having simple means whereby the same may be 15 introduced into a well casing and securely and positively engaged with a collar to be expanded, spread, or burst so that that section of casing immediately below the collar to be burst may be parted from the sections 20 of casing above.

Further the invention forming the subject matter of this application aims to provide a collar burster in which a pair of spreaders or bursting pawls is employed, 25 the attaching portions or ears of the pawls being flatly engaged with each other so as to relieve the pivots which support the pawls of excessive strain and so that the lateral stress incident to bursting the collar is 30 borne principally if not entirely by the pawls themselves.

A further object is to provide a collar burster or expander wherein simple means is provided to allow the pawls to assume 35 their inoperative positions subsequent to bracing the collar so that the device may be conveniently withdrawn from the well without damaging the sections of the casing above the previously burst collar.

40 A further object is to provide a collar burster for wells which is of highly simplified construction, durable in use and cheap to manufacture.

Other objects and advantages of the invention will be apparent during the course 45 of the following description.

In the accompanying drawing forming a part of this application and in which like numerals are employed to designate like 50 parts throughout the same

Figure 1 is a side elevation of the improved collar burster or expander, parts being broken away to illustrate the several pawls and the means to support the same.

55 Figure 2 is a side elevation of the im-

proved collar burster, the view being taken at right angles to Figure 1.

Figure 3 is a horizontal sectional view taken on line 3—3 of Figure 2.

Figure 4 is a side elevation of a cap or 60 detachable section which is positioned in one side of the body in the manner illustrated in Figure 2.

In the drawing wherein for the purpose of illustration is shown a preferred embodiment of the invention the numeral 5 designates a body having its rear portion formed with a slightly tapered attaching stem 6 by means of which the same may be connected to a drill stem and as illustrated in Figures 1 and 2 the opposite sides of the body may be formed with flattened faces 7 with which the jaws of a wrench may be engaged when it is desired to either attach or detach the device.

In carrying out the invention the forward portion of the body 5 is provided with a transversely extending opening 10 which extends out through opposite sides of the body and receives a pair of pawls 11. It will be 80 observed that the inner longitudinal edges of the pawls 11 flatly contact with the inclined walls or edges of the depending member 12 arranged within the opening 10 and the member 12 thereby limits the inward 85 movement of the pawls so that during the descent of the device the pawls will be in position to swing outwardly into engagement with the collar to be burst.

During the descent of the device the rollers 14 of the pawls 11 rotatably contact with the wall of the well casing and thereby hold the pawls in their inoperative positions and it might be stated that the rollers 14 reduce friction to a minimum.

The pawls 11 are formed with attaching barrels or ears 16 which are rotatably mounted on the cylindrical heads 18 of the pivot bolts 19, the said pivot bolts 19 being tightly threaded into sockets 21 provided in the body for that purpose. Figure 2 illustrated that one side of the body is formed with an opening 20 for the reception of a cap or cover member 24 which extends over the pawls 11. The closure or cap 24 is formed with cylindrical openings 25 for the reception of the cylindrical heads 18 and with reference to Figure 3 it will be seen that the heads 18 do not project beyond the periphery of the body and there-

fore they do not retard the descent of the device.

Attention is directed to the fact that a dove tail connection is provided between the 5 detachable section 24 and the body and this dove tail connection cooperates with the cylindrical heads 18 in holding the detachable section in position. In other words the dove tail connection between the 10 detachable section 24 and the body 5 holds the detachable section against movement laterally away from the body while the cylindrical heads 18 hold the detachable section against sliding movement in the opening 20 within which it is normally located.

However, when assembling the device the bolts 19 are, of course, not in place and the detachable portion 24 is also detached. The 20 pawls 11 are first placed in position and the detachable section 24 is then positioned within the opening 20. The pivot bolts 19 are now extended through the openings 25, the ears 16 and into the sockets 21 whereby the pawls 11 are rotatably supported. It is thus seen that when the bolts 19 are positioned, as illustrated in Figure 3 they not only rotatably support the pawls 11, but also hold the detachable section against displacement.

When preparing the device for descent in 30 the well casing the pawls 11 are swung upwardly into the V-shaped branches 40 of the opening 10 and the device may now be lowered as previously stated. The rollers 14 hold the pawls in their inoperative positions and when the desired collar or point is reached a slight upward pull is exerted on the device so that the pawls 11 will assume their operative positions. That is to say the outer portions of the pawls will be 40 positioned between the threaded ends of the sections of casing and within the collar. Continued upward movement of the device will burst the collar or expand the same so that it is released from threaded engagement 45 with the section of casing immediately below. It is believed to be well understood that the casing is sometimes frozen or anchored in the lower portion of a well so that it cannot be conveniently removed and 50 thus this invention enables the sections which are not anchored to be separated from the anchored section. When those sections of the casing above the anchored section have been removed the anchored section may be 55 drilled up and removed in small pieces or otherwise treated.

When the pawls 11 swing outwardly the flat outer ends 50 of the same will flatly engage the collar between the threaded ends 60 of the sections and when the device is withdrawn the flat edges 51 are engaged with the collar. When the desired operation has been performed the outer terminal portions 65 of the pawls drop into the branches 54 of the opening 10 and consequently the device

may be conveniently removed. Attention is directed to the fact that the rollers 14 are not located at the ends of the pawls but at the sides of the same and consequently these pawls do not in any way interfere with the 70 bursting operation.

It will be seen with particular reference to Figures 1 and 3 that the rounded inner ends or barrels 16 of the pawls 11 have rolling contact with each other so that the strain 75 on the pawls incident to expanding the collar is borne solely by the pawls. By thus causing the pawls to entirely bear the strain of the expanding operation the pivot pins 8 will not be bent or mutilated and the device 80 will be capable of use for a long period.

It is to be understood that the form of the invention herewith shown and described is to be taken merely as a preferred example of the same and that such minor changes in 85 arrangement and construction of parts may be made as will remain within the spirit of the invention and the scope of what is claimed.

I claim:—

1. A collar expander for wells comprising a body having an opening extending out through opposite sides thereof, pivot pins extending through said opening, and pawls 95 rotatably mounted on said pivot pins and having their rear ends in rolling contact with each other whereby to relieve the pivot pins of the strain incident to the engagement of the pawls with a collar to be expanded.

2. A collar expander for wells comprising a body having an opening extending out through opposite sides thereof, spaced pivot pins extending through said opening, and pawls rotatably mounted on said pivot pins and having rollers the inner portions of 100 said pawls having rolling contact with each other whereby the strain incident to expanding a collar is borne solely by the pawls.

3. A collar expander for wells comprising a body, and pawls pivoted thereto and having their inner portions in rolling contact with each other whereby the strain incident to the engagement of the pawls with the 105 collar to be expanded is borne entirely by the pawls.

4. A collar expander for wells comprising a body having an opening, pawls pivotally supported within the opening and having their inner portions in rolling contact with each other whereby the entire strain on the 110 pawls incident to expanding a collar is borne solely by the pawls, there being means within the opening to limit the inward swinging movement of the pawls.

5. A collar expander for wells comprising a body having an opening extending out through opposite sides thereof, pivot pins extending through said opening, and pawls 115 rotatably mounted on said pivot pins and

having rollers, said body being provided at one side of said rollers with a detachable portion, said pivot pins engaging said detachable portion whereby to hold the same 5 against endwise movement.

6. A collar expander comprising a body having an opening extending out through opposite sides thereof, pawls arranged within said opening and having their outer ends 10 flat for engaging a collar to be expanded, antifriction means carried by the outer edges of said rollers and adapted for engaging the interior of a well casing, there being a V-shaped depending member within

said opening and having inclined walls arranged within the path of travel of said pawls whereby to limit the inward swinging movement of the same, and pivot bolts having heads rotatably supporting said pawls, said body being provided at one side of said 15 pawls with a detachable portion having a dove tail connection therewith, said detachable portion being provided with openings receiving said pivot bolts whereby the pivot bolts and the dove tail connection between 20 the detachable section and the body hold the detachable portion firmly in position.

JAMES A. WOODS.
